UNITED STATES PATENT OFFICE.

EDWARD H. BURDICK, OF SYRACUSE, NEW YORK.

DESIGN FOR A HANDLE FOR SPOONS OR SIMILAR ARTICLES.

SPECIFICATION forming part of Design No. 35,321, dated November 26, 1901.

Application filed September 30, 1901. Serial No. 77,157. Term of patent 7 years.

To all whom it may concern:

Be it known that I, EDWARD H. BURDICK, a citizen of the United States, residing at Syracuse, in the county of Onondaga and State of New York, have invented and produced a new and original Design for a Handle for Spoons or Similar Articles, of which the following is a specification, reference being had to the accompanying drawings, forming part thereof.

Figures 1 and 2 of the drawings represent front and back views, respectively, of a spoon, showing my new design.

As illustrated in said drawings, the leading or material feature of my design consists of the artistic arrangement of the representations of certain emblems or symbols which appear in two groups, one group being disposed on the front of the spoon-handle and the other group disposed on the back thereof, and each group being associated with suitable ornamental scrolls.

The handle A is formed with an enlarged outer end portion B, and upon the front of said portion are provided two panels C and D, and upon the back of said enlarged portion are provided two similar panels C' and D'.

The first-named group of emblems or symbols comprises the following, viz: the representation of a human eye arranged in the panel C, as indicated at a, and surrounded by a plurality of radiant lines, a letter "G" arranged in said panel and inclosing said eye, the representation of a builder's square and a compass arranged in the panel D, as indicated at b and c, respectively, and the representation of a builder's plumb arranged below said square and compass, as shown at d.

The borders of said panels C and D are ornamented with scrolls, and below the panel D appear ornamental configurations, as shown 40 in Fig. 1. The other group of emblems or symbols comprises the representation of a plumb-level (indicated at a' in the panel C') and the representation of a measuring-ruler and a hammer arranged in the order named 45 below said plumb-level, as indicated at b' and c', respectively, the said ruler extending transverse of the panel and the hammer having its handle extending toward the panel D'. Said panel D' appears plain, and below it is 50 arranged the representation of a trowel, as indicated at d', the handle of which trowel extends toward the panel. The borders of the panels C' and D' are ornamented with scrolls differing somewhat from the scrolls on 55 the panels C and D, and the handle of the spoon is otherwise ornamented adjacent to the aforesaid trowel, as clearly shown in Fig. 2.

It is apparent that the plain panel D' may be utilized for various inscriptions. 60

Having described my invention, what I claim as new, and desire to secure by Letters Patent, is—

The design for a handle for spoons or similar articles, substantially as shown and described. 65

In testimony whereof I have signed my name to this specification in the presence of two subscribing witnesses.

EDWARD H. BURDICK. [L. S.]
